ROOFING

Martin G. O'Reilly, Chicago, Ill., assignor to Ford
Roofing Products Company, Chicago, Ill., a cor-
poration of Illinois

Application December 14, 1936, Serial No. 115,700

5 Claims. (Cl. 108—8)

This invention relates to roofing and particularly to shingle roofing and the shingle units therefor, and among other objects aims to provide a shingled roof covering having improved protective qualities without sacrifice of economy or appearance.

The invention may be readily understood by reference to one illustrative embodiment thereof shown in the accompanying drawing.

In said drawing:

Fig. 1 is a plan view of a shingled roof;

Fig. 2 is a perspective view of a portion of the roof illustrating the arrangement of the shingle units and the roof texture or appearance produced thereby;

Fig. 3 is a fragmentary section taken on the plane 3—3 of Fig. 2, illustrating the fastening of the shingle units; and

Fig. 4 is a plan view of a single shingle unit.

The invention is here shown embodied in what is known in the trade as Dutch-lap roofing. Such roofing is characterized by economy of roofing material; indeed, it produces a larger shingled area per unit of roofing material than any other practical form or arrangement of shingles. While Dutch-lap roofing is widely used for the foregoing reasons, it is monotonous in appearance and does not afford a sufficient factor of safety against leakage, particularly in faulty or improper application. This is a major defect, since the roof when laid gives no visual evidence of faulty or improper application, thereby affording a temptation to applicators to cheat by reducing the amount of overlap in order to save shingles. These faults are inherent in the design. When the shingles are laid, the head lap and the side lap should not be less than a prescribed minimum which will prevent leakage under ordinary conditions. However, when laid, one cannot readily determine whether the minimum requirements were observed. Even with honest intentions, the applicator cannot readily maintain alignment of the shingle courses and therefore periodically corrects for lack of alignment or obliquity of the courses by decreasing the head lap or side lap in one or more courses, thereby leaving the roof vulnerable to leakage at these points.

These faults are overcome in the illustrative roofing, which is not only attractive in appearance but provides adequate protection against leakage without reduction in characteristic economy and which embodies means for preventing faulty and fraudulent application.

The illustrative shingle unit 10 is generally rec-

tangular in shape and, as here shown, is laid in the conventional Dutch-lap fashion, that is, with the shingles of each course 11 overlapped with a side lap *a* and with each successive course overlapping the next lower course with a head lap *b*, to afford adequate protection against leakage. The side and head laps should not be less than a predetermined minimum. In the shingle unit here illustrated, in which the length of the lower exposed edge of the unit is about 18 inches and its depth about 12 inches, the side lap *a* should preferably be about 4 inches and the head lap *b* about 2½ inches.

To prevent violation of the minimum overlap requirements, the shingle units are provided with gauging means which visually reveal a departure from the required overlap and which also greatly facilitate the proper laying and alignment of the shingle units and the shingle courses.

The aforesaid means are embodied in the units by changing the contour of the edge of the unit at the point representing the amount of lap. To control the side lap, the lower edge 12 of the shingle unit is, in this instance, offset as at 13 by an amount equivalent to the side lap. Preferably, the opposite end of the lower edge of the unit is also similarly offset as at 14, so that the overlapping portions of the lower edges of adjacent shingles will be in alignment as at 15 (Fig. 2) to bring the shingles into relief and to provide contrasting shadow lines of double thickness, thereby assisting in eliminating the monotony which has heretofore characterized Dutch-lap roofing and giving the roofing the highly desired textured surface. The amount of offset of the ends of the lower edge of the shingles need not be great; in the present instance, it is about ½ inch. In laying the shingles, it is simply necessary to overlap their side edges to bring the edge 16 of one unit into alignment with the shoulder 17 of the underlying unit. While in this instance the underlapped side edge 11 of one unit lies in alignment with the shoulder 18 of the overlapping unit, this is not essential to the design. In other words, the length of the offset portions 13 and 14 on the shingle unit need not be equal, but it is preferable that the length of the offset portion 14 be at least as long as the offset portion 13.

If the side lap be not maintained, it is obvious that lack of alignment of the side edge 16 and the shoulder 17 will at once reveal this fact.

The gauging of the head lap and aligning of the overlapping courses is represented by a mark on the underlapped side edge of the shingle unit

at 18 at a point distant from the lower edge of the shingle unit equivalent to the head lap 5, which mark is formed by changing the contour of the side edge of the unit at the point 18. The portion 28 of the side edge below the point 18 is here shown extending at right angles to the lower edge of the shingle and the portion 21 above the mark is shown inclined thereto. The vertex of the angle formed by the portions 28 and 21 establishes the mark 18. The aforesaid mark is used to effect the proper head lap by aligning the mark with the upper edge 22 of the underlying shingle course. The opposite end of each unit is properly aligned by registering its upper edge with the upper edge of the next adjacent unit in that course which has been previously positioned. Failure so to register such upper edges will be revealed in lack of registration of the aforesaid portions 13 and 14 along the lower edge of the unit. The longitudinal location of a shingle unit is determined by abutting its edge 28 against the upper portion 27 of the side edge 18 of the unit in the next underlying course (see Fig. 1).

Even though a given shingle be improperly aligned in its course, the obliquity of one shingle cannot be perpetuated in the course, since the mark 18 of the next shingle must be located in alignment with the upper edge 22 of the lower course. In other words, the faulty placing of one shingle slightly oblique to the proper direction of the course does not influence the location of the next shingle which must be laid with its mark 18 in register with the upper edge 22 of the lower course. Thus the head lap is not progressively reduced as is often the case in the ordinary Dutch-lap roofing where the erroneous placing of one shingle may be cumulative throughout the course, or at any rate, is not detected in season to prevent a drastic adjustment and consequent insufficient protection.

In the present instance the inclined portion 21 of the side edge of the unit terminates at a point 23 and the balance 24 of the edge continues at right angles to the longitudinal edge of the shingle (or parallel to the portion 28) for a distance equal to the length of the portion 28, thereby making the ends of the shingle units reversely complementary as illustrated in dotted lines of Fig. 4. This not only provides a supplemental gauge mark at the point 23, but effects a substantial economy in the use of material by permitting a substantial side lap a, while employing no more material than if the side lap were only one-half as great. While the side lap c at the upper edge of a course of shingles is only one-half that of the side lap a, this does not reduce the effective protection against leakage, inasmuch as water creeping under the side edge 18 of a unit at, say, the point 25 does not travel in a horizontal line to the portions 21 and 24 of the side edge of the underlapped unit, but under the action of gravity, travels downwardly, as illustrated by the curved dotted line 26, into the region of wider overlap.

As added protection against leakage, the exposed side edge of each shingle unit is prevented from curling or being blown up to reduce the effective overlap by fastening down the lower exposed corner 28. The tendency to curl or be blown up is generally encountered in roofing of this character, namely prepared asphalt roofing, because it not only is sufficiently flexible to yield to a driving wind or rain, but curls under the action of heat and sun, if the free portions or corners of the shingles are not fastened down.

The fastening is here shown in the form of a staple 29 which passes through the corner 28 and the underlying unit and is clinched between the latter and the lowermost thickness of material (see Fig. 3).

In laying a roof, each unit is preferably fastened down by a nail 30 driven through the lower right-hand corner of each unit. Such nail penetrates also the underlying portion of a shingle 31 in the next lower course. This nail is covered 10 by the overlying corner 28 of the next shingle. Preferably also, a nail 32 is driven through the upper left-hand corner of each unit (see Fig. 1). Such nail penetrates also the underlying side margin of the preceding shingle in that course. 15 While two nails for each shingle are not essential, they do prevent the shingle from twisting out of place before the next course of shingles is laid.

It should be noted that the corner areas 33 and 34 (represented by the dot and dash rectangles in Fig. 1) in which the nails may properly be placed are substantially large. This is important, particularly in applying the roofing over an old roof wherein the underlying roof boards 25 are not exposed. If a roof board be not encountered, the nail may be redriven at any point in the aforesaid areas 33 and 34 in which a roof board can be located.

Obviously the invention is not limited to the 30 details of the illustrative construction, since these may be variously modified. Moreover, it is not indispensable that all features of the invention be used conjointly since various features may be used to advantage in different combinations and sub-combinations.

Having described my invention, I claim:

1. Roofing of the character described comprising in combination a plurality of overlapping courses of shingle units, the units of each course being lapped along their side margins by adjacent units, the extremities of the lower edge of each unit being offset predetermined distances from the respective side edges, said offset portions being in alignment and the side margin of the overlapping unit being in alignment with the extremity of the underlying offset, a portion of the underlapping side edge of each unit diverging toward the lower edge of the course and terminating at a predetermined distance from the lower edge of the unit, said point of termination of each unit being located in register with the upper edge of the next underlying course.

2. Roofing of the character described comprising in combination a plurality of overlapping courses of shingle units, the units of each course being lapped along their side margins by adjacent units to provide a Dutch-lap arrangement of shingles, the lower edges of each unit being offset adjacent the side of the shingle by distances equivalent to the amount of side lap at the lower edges of such units, the offset portions of the edges of overlapping units in a course being in register thereby to form offsets in the outline of the lower edge of each course which provide 65 visual indications that the units have the desired side lap, a portion of the underlapping side edge of each unit being inclined to the lower edge of the unit, said inclined portion terminating a distance from the said lower edge equivalent to the 70 amount of head lap of said courses, said point of termination providing a shoulder, said shoulders of each unit registering with the upper edges of the units of the next course.

3. A shingle unit of the character described 75

comprising a body made of flexible roofing material, the lower edge of the unit being offset at each end, the length of the offset portion being equal to the desired side lap of the unit when laid in a roof, said offset portions of adjacent units in a course being adapted to be overlapped in register to provide offsets in the lower edge of a course of units, and one side edge of the unit diverging outwardly toward the lower edge, the 5 diverging portion of said side edge terminating short of the lower edge by a distance equivalent to the desired head lap of the unit when laid in a roof.

4. Roofing of the character described comprising in combination a plurality of overlapping courses of generally rectangular shingle units, the units of each course being lapped along their side edges to provide a Dutch-lap arrangement of shingles, each end of the lower edge of each unit 10 being offset for a distance equal to the desired amount of side lap, the offset portions of overlapping units being in register thereby to insure the desired side lap and to aline units with each

other, a side edge of said unit being provided with a shoulder spaced from the lower edge of the unit a distance equal to the amount of head lap of said courses, the shoulders of each unit being in register with the upper edge of the next lower course and the opposite upper corner of each unit being in alinement with the upper edge of the adjacent unit of that course.

5. Roofing of the character described comprising in combination a plurality of overlapping 10 courses of shingle units, the units of each course being lapped along their side margins by adjacent units to provide a Dutch-lap arrangement of shingles, the lower edge of each unit being offset adjacent the sides of the shingle by distances equivalent to the amount of side lap at the lower edge of such units, the offset portions of the edge of overlapping units being in register thereby to form offsets in the outline of the lower edge of each course which provide visual indications that the units have the desired side lap. 15 20
